UNITED STATES PATENT OFFICE.

OLE M. DAHL, OF BOSTON, MASSACHUSETTS.

HAT-SECURING DEVICE.

1,137,843.

Specification of Letters Patent.

Patented May 4, 1915.

Application filed June 5, 1914. Serial No. 843,281.

To all whom it may concern:

Be it known that I, OLE M. DAHL, a citizen of the United States, and a resident of Boston, county of Suffolk, and Commonwealth of Massachusetts, have invented an Improvement in Hat-Securing Devices, of which the following description, in connection with the accompanying drawings, is a specification, like characters on the drawings representing like parts.

This invention aims to provide, as a new article of manufacture, an improved device for securing a hat to the head.

While my invention is particularly adapted for use in connection with women's hats, it may also be used to advantage in connection with men's hats.

In the drawing of one embodiment of my invention selected for description and illustration herein: Figure 1 is a view of the under side of the crown of a woman's hat of conventional form, showing my improved securing means in position thereon, the hat edge being shown in parallel dotted lines, and the outline of the head represented by a single dotted line; Fig. 2, a detail of the locking and adjusting means, and showing the latter as it appears in position on an article of headwear, a portion of said article only being shown. Fig. 3, a vertical sectional view on the line 3—3, Fig. 2, from the left and on an enlarged scale.

My invention, as illustrated, see Fig. 1, comprises a flexible, preferably resilient, head engaging member, as a band 1, of convenient breadth and thickness and of suitable material, as for instance, copper or brass, preferably covered with any desired material 2, as cloth, to render it comfortable for the head. This head engaging band 1, at or near each of its ends is provided with a laterally extended post 3, see Figs. 1 and 3, which posts carry each a head 4, which may be of any desired configuration and preferably somewhat ornamental. These posts may be secured to the band ends in any preferred manner, as by being extended therethrough and headed over. The heads 4 may also be secured to the posts 3 by extending the posts therethrough and heading them over, the posts being made of some suitable, relatively soft metal for that purpose, so that they may be readily headed over by any one with an ordinary small hammer. For engaging the opposite ends of the band 1, and locking them in adjusted

positions, I have provided a band locking member 5 which may be of any desired material, as metal, and is preferably fashioned into a more or less ornamental form to become an ornament to the hat. The outer ends of the posts 3 are each received in the longitudinal slot 6 of the band locking member 5.

The slot 6, see Fig. 2, may be as long as necessary and herein extends substantially the length of the member 5. The lower edge of this slot is provided with a series of post engaging teeth or serrations 7 inclined in opposite directions from the approximate longitudinal center of the slot and these serrations are connected by round fillets therebetween, supplying convenient seats for the posts 3, which may be made of a size to snugly fit therein. By means of these teeth or serrations, the posts 3 may be positioned at will relatively to each other in the slot 6, and thus the circumferential dimension of the band 1 be lessened or increased as desired to fit one's head.

For retaining the posts securely in adjusted position, I have provided a post retaining member 8, as a spring for instance, secured at its ends to the member 5 and, see Figs. 1, 3, bearing normally on the upper edges of the posts and acting thereby to hold them in proper adjusted position but permitting them, however, to be moved at will by flexing the spring.

The manner of using my improved hat securing means is as follows: The band 1 being made of such length that it, by means of the locking member 5 may be adjusted to fit any head within certain limits, is first secured to the inside of the lower portion of the crown of the hat, adjacent the rim 11, dotted lines, Fig. 1, by any suitable means, as for instance, a loop 9 which may be secured to the inside of the rim of the hat at or near the back thereof. The two ends of the member 1 are then thrust through vertical slots 10 at or near the opposite end of the hat 12, indicated by dotted lines Fig. 1; the posts 3 are next thrust through the slot 6 in the member 5, see Fig. 2, and the heads 4 positioned on the outer ends of the posts 3, which posts are then headed over, as by a few taps of a small hammer, as desired, thus securely fastening the heads 4 thereon. The band having been thus secured to the hat as described, the hat may be placed upon the head and the posts

3 drawn toward each other in the slot 6 by the fingers, until the band is sufficiently tight about the head to hold the hat securely thereon. The posts are then each dropped 5 behind one of the teeth or serrations 7, the spring 8 acting to hold them therein. To remove the hat it is necessary only to release the posts 3 from their positions behind the teeth 7 and permit the band 1 to spring 10 open and thus release itself from contact with the head.

I have found that by the use of this device the hat may be securely fastened to the head without inconvenience and without the 15 bother of hat pins which, through extended use, perforate the hat with a multitude of holes and thus mar its appearance and seriously injure it. The hat pins are also more or less dangerous, as they are frequently 20 thrust into the head by mistake. Furthermore, the protruding points of the hat pins when made unnecessarily long are a constant source of danger to others.

I am aware that adjustable hat sweat 25 bands have been constructed for use upon men's hats, but these are not hat securing members and moreover are not adapted for use in connection with women's hats. These 30 devices have usually been constructed so that they are adjustable only from the inside of the hat and therefore are not adapted for use as hat securing members. Furthermore, my improved device is so constructed as to have little or no resemblance to a mechanical device and is, therefore, not objectionable 35 in appearance, but is on the contrary, ornamental.

My improved securing device as described

is inexpensive to make and therefore it may be fitted to the hat and left thereon, it being convenient to have one on each hat and thus avoid the necessity of removing it from and subsequently replacing it on the hat.

Obviously many detail changes may be made in the foregoing described construction without departing from the spirit of my invention and within the scope of the following claims.

Claims—

1. As a new article of manufacture, a hat 50 securing device comprising a head engaging band provided at each end with a post, a locking member for said band ends provided with a slot for said posts, post engaging means on one edge of the slot, post retaining means on the locking member whereby the posts may be locked in position on the locking member at will, and the effective length of the band thereby determined.

2. The combination of an article of headwear with an expandible head encircling and engaging band substantially all within the article of headwear, the ends only of the band extended through relatively adjacent apertures in the article of headwear, and means entirely without said article and engaging the band ends for adjusting the circumferential dimension of the head engaging band.

In testimony whereof, I have signed my name to this specification, in the presence of two subscribing witnesses.

OLE M. DAHL.
